CLAIM

The ornamental design for a system for dispensing chemical deterrents, as shown and described.

DESCRIPTION

FIG. 1 is a front top left perspective view of a system for dispensing chemical deterrents showing my new design; FIG. 2 is a front top right perspective view thereof; FIG. 3 is a front bottom left perspective view thereof; FIG. 4 is a front elevational view thereof; FIG. 5 is a back elevational view thereof; FIG. 6 is a top plan view thereof; FIG. 7 is a bottom plan view thereof; FIG. 8 is a right elevational view thereof; and, FIG. 9 is a left elevational view thereof.

The broken line showing of the tubes in FIGS. 1 through 9 is included for the purpose of showing environmental structure and forms no part of the claimed design.
